3,202,081
VENTILATOR
Loren Cook, Berea, Ohio, assignor to Loren Cook
Company, a corporation of Ohio
Filed Apr. 9, 1964, Ser. No. 358,571
10 Claims. (Cl. 98—43)

My invention relates to ventilators and more particularly to roof ventilators that are compact in design and quiet and efficient in operation, and is a continuation-in-part of my application Serial No. 228,558, filed on October 5, 1962.

In roof ventilators as heretofore constructed, the area in the motor compartment is frequently insufficient to accommodate a comparatively large motor. Another serious defect in prior roof ventilators is the lack of proper ventilation to cool the motor. In ordinary ventilators and particularly those in which the blower wheel is rotated by a motor through a belt drive, the normal heat build-up in the motor compartment adversely affects the bearings and also causes rapid belt deterioration which eventually causes cracking and segmentation of the belt and this is particularly true when the air being exhausted through the ventilator is at a temperature of approximately 150° Fahrenheit or higher.

In accordance with my invention, I have provided an improved ventilator which while being compact in design has a compartment which is large enough to accommodate a comparatively large motor. Ventilating means are also provided through which air flows to cool the motor and in which the discharge of air from the ventilator causes the flow of air through the motor compartment to increase as the speed of the motor and the blower wheel increases to thereby dissipate the heat generated by the increased speed of the motor. In my improved ventilator, means are also provided to reduce pressure and turbulence loss and to provide a substantially constant pressure within the blower compartment.

It is therefore an object of my invention to provide a ventilator including a motor compartment having an air inlet opening and an annular opening for the discharge of air therefrom and in which the ventilator is provided with an annular opening for the discharge of air from a room or building which opening is arranged below an annularly downwardly inclined baffle, the upper portion of which is arranged in close proximity to an air discharge outlet from the motor compartment to thereby create a negative pressure above the baffle during the discharge of air through the ventilator which draws air from the motor compartment through its outlet opening and causes air to flow into the motor compartment through the air inlet opening.

Another object of my invention is to provide a roof ventilator having a motor compartment, annular inlet and outlet openings through which air is circulated through the motor compartment to cool the motor and in which the ventilator is provided with an annular discharge opening leading from the blower compartment which is so arranged that as air flows outwardly through the discharge opening of the blower compartment, it causes air to circulate through the motor compartment which circulation of air increases as the rotative speed of the motor and blower is increased.

A further object of my invention is to provide an improved roof ventilator including a blower wheel provided with air foil blades in which a venturi-shaped conduit means extends into the chamber containing the blower wheel and in which a wall surrounds and extends upwardly in parallel relation to the lower portion of the blades of the blower wheel which causes the blower wheel to operate under a slight internal pressure to thereby improve

2

the efficiency of the blower wheel and to provide a structure that is quiet and more efficient in operation than previous ventilators.

A still further object of my invention is to provide an improved roof ventilator including a blower compartment into which a duct means extends and in which a vertical wall surrounds the lower portion of the blower wheel which causes the blower wheel to operate under a slight internal pressure to thereby improve its efficiency and in 10 which the cross sectional area of the discharge opening from the blower compartment is substantially equal to the cross sectional area of its air inlet means to thereby provide a substantially constant pressure within the blower compartment.

Other objects and advantages of my invention will become apparent as the specification proceeds.

My invention will be better understood by reference to the accompanying drawings in which:

FIG. 1 is partly an elevational view and partly a sectional view of my improved ventilator;

FIG. 2 is a plan view taken on a plane passing through the line 2—2 of FIG. 1 showing parts in section;

FIG. 3 is an enlarged detail view showing the connection between the supporting posts of the ventilator;

FIG. 4 is an enlarged detail view showing the connection between an upwardly extending annular wall and the upper baffle of the blower compartment;

FIG. 5 is a cross sectional view of another form of my ventilator;

FIG. 6 is a view similar to that shown in FIG. 5 but showing a belt drive for rotating the blower wheel;

FIG. 7 is a cross sectional view taken on a plane passing through the line 7—7 of FIG. 6;

FIG. 8 is a view similar to that shown in FIG. 1 with the exception that the blower is driven directly from the shaft of the motor and an annular opening is provided for the entrance of air to the motor compartment; and

FIG. 9 is an enlarged sectional view of a connection between the upwardly extending wall forming part of the motor compartment and the dome which provides an annular opening into the motor compartment.

One form of my invention is illustrated in FIGS. 1 to 4 of the drawing in which a base portion 1 is provided which is adapted to be supported on a curb extending upwardly from the roof as shown in FIGS. 5 and 6 of the drawing and which terminates in an upwardly extending throat or duct portion 2, the axis of which is in alignment with the axis of the ventilator and which serves as a support for other parts of the ventilator. In my improved ventilator the parts are arranged to provide a blower compartment 3 and a motor compartment 4, a discharge outlet from the blower compartment, and an air inlet and discharge openings through which air may be circulated through the motor compartment to cool the motor. For supporting the upper portion of the ventilator, an annular wall designated generally by the numeral 5 is provided, part of which extends vertically or substantially vertically upwardly relative to the base portion 1. As shown, the wall includes an annular flange 6 which is secured to the throat 2 by suitable means, such as rivets, and a portion of which extends radially outwardly as indicated by the numeral 7, and then vertically upwardly as indicated by the numeral 8 and terminates in an inverted U-shaped flange 9 which forms the lower portion of the ventilator discharge opening.

For supporting the outer portion of wall 5, a plurality of posts 10 are provided, each of which has upper and lower similarly threaded apertures, the upper one of which is shown in FIG. 3. Each of the posts 10 is secured to the upper wall of base 1 by suitable means, such as a screw threaded into the lower aperture in post 10, the head of which bears against the lower portion of base 1.

As shown in the drawings, a plate 11 extends radially across the ventilator forming a cover for the blower compartment and a support for the motor 12 which is secured thereto by suitable means, such as bolts and nuts 13. The plate 11 separates the motor compartment from the blower compartment and terminates in a downwardly and outwardly extending annular baffle 14 which forms the upper wall of an annular discharge opening from the blower compartment which extends between the baffle 14 and the flange 9 of wall 5 and means are provided for maintaining plate 11 and baffle 14 at a predetermined distance from the flange 9 and while any suitable means may be provided for this purpose, as shown, a series of spaced apertures is provided in the U-shaped flange 9, each of which is arranged in alignment with the threaded aperture in a post 10, and a screw 15 which extends through an aperture in flange 9 is threaded into the aperture of a lower post. A series of upper posts 16 are also provided, each of which has an aperture in its lower portion which is threaded on to the upper portion of one of the screws 15 to thereby hold the lower ends of posts 16 in engagement with the flange 9.

To provide a comparatively large compartment for motor 12 as shown in FIG. 1, an annular wall 17 extends upwardly in a substantially vertical direction from the radially extending portion 18 of baffle 14 and terminates in a dome-shaped portion 19 and means are provided to fasten posts 16 to the radially extending portion 18 of baffle 14 and to maintain wall 17 in spaced relation thereto to provide an annular outlet opening 20 from the motor compartment as shown more particularly in FIG. 4. For this purpose, a plurality of angularly-shaped brackets are provided each of which has an arm extending upwardly from the radially extending portion 18 of baffle 14 which has a threaded bushing 22 therein to receive the threads of a wing nut screw 23 and the other arm of which has an opening therein to receive the shank of a screw 24 which also extends through an opening in the radially extending portion 18 of baffle 14 and is threaded in an upper aperture in one of the posts 16. Means are also provided for permitting air from the atmosphere to enter the motor compartment. For this purpose, a plurality of spaced louvers 25 may be provided in the dome or the dome 19 may be spaced from wall 17 to form an annular opening as shown in FIGS. 8 and 9.

The blower wheel may be driven by a motor directly as shown in FIGS. 5 and 8 or it may be provided with a belt drive as shown in FIGS. 1 and 6. The blower wheel is arranged in the blower compartment and consists of an upper plate 25a and a plurality of blades 26 which are secured to plate 25a in any desired manner. To provide quiet operation of the blower, each of the blades is of the air foil type and as shown is provided with a flange 27 which is riveted to plate 25a.

In the form of the invention shown in FIGS. 1 to 4, the blower is driven by a shaft 28 which extends through bearings 29 and 30 which may be supported in any suitable manner. As shown in FIGS. 1 and 2 and also in FIGS. 6 and 7, a frame is provided consisting of side walls 31 and 32 between which upper and lower cross pieces 33 and 34 extend which form supports for bearings 29 and 30.

As shown in FIG. 1, the lower portion of shaft 28 extends through the cross piece 34 and plates 11 and 25a and terminates in a hub 35 to which it may be secured by any suitable means, such as a set screw, not shown. Hub 35, in turn, has a flange 36 secured thereto which is secured to plate 25a by suitable means, such as bolts, and prevents entrance of air from the blower compartment into the motor compartment through the aperture through which shaft 28 extends. The shaft 28 serves to support the blower in its desired rotatable position. The upper end of shaft 28 also extends into a hub 37 having a pulley 38 secured thereto.

The motor 12 may be secured to the supporting frame

5 in any suitable manner. As shown, it is secured to a bracket 39 which in turn is secured to the side walls 30 and 31 and its shaft extends into a hub 40 having a pulley 41 secured thereto which is arranged in alignment with pulley 38 on the drive shaft 28 and a belt is trained around the pulleys 38 and 41 to transmit motion from the motor shaft to the drive shaft when motor 12 is energized.

10 Side walls 31 and 32 may be secured to plate 11 in any suitable manner. As shown each side wall is provided with a flange 42 and 43, respectively, and bolts, each having its head engaging the lower side of plate 11, extends through the respective flanges and are held in place by nuts 44. To minimize vibrations, collars formed of a 15 resilient material, such as rubber, preferably surround each of the bolts extending between plate 11 and flanges 42 and 43 as shown more particularly in FIG. 6.

20 In my improved ventilator as shown in FIGS. 1 to 4, the throat or duct means 2 extending upwardly from base 1 has a venturi-shaped upper portion opening into the blower compartment and the vertically extending portion of wall 5 cuts off air which is forced outwardly by the lower portion of the blower, thus permitting the blower wheel to operate under a slight internal pressure which 25 improves its efficiency and which provides with the air foil blades a ventilator that is especially quiet in operation. The vertical portion 3 of wall 5 also prevents back pressure into the ventilator and is spaced at such a distance from the baffle 14 that the cross sectional area at the outlet of the blower wheel is equal to or substantially 30 equal to the cross sectional area at its inlet opening, thereby providing a constant pressure in the blower compartment.

35 During the operation of the blower, the discharge of air through the annular space between the downwardly and outwardly extending baffle 14 and the flange 9 creates a negative pressure above the baffle 14 which causes air to be drawn outwardly through the annular opening 20 between wall 17 and the radially extending portion 18 of baffle 14 which air is replenished by air 40 flowing into the motor compartment through the louvers 25. The rotative speed of the blower wheel of course depends upon the rotative speed of the motor shaft. As the speed of the motor is increased, more heat is generated but because the speed of the blower is likewise increased the negative pressure above baffle 14 is increased which causes an increase in the flow of air through the motor compartment to cool the motor. As shown, electrical conductors 45 connected to a suitable source of 45 electrical energy extend through an opening in the base 1 and through tube 46 to the motor.

50 In the form of my invention shown in FIGS. 1 and 2, the downwardly and outwardly extending baffle 14 while permitting the discharge of air from the blower, prevents the entrance of weather elements, such as snow, sleet or rain. It will also be noted that the motor supporting plate 11 is arranged above baffle 14 and its peripheral portion is bent downwardly which not only strengthens the motor plate but also provides a wall 47 which limits the distance that weather elements, such as snow, rain, or sleet may enter the motor compartment and consequently any rain or melted snow or ice that passes through the annular opening 20 will drain over the outer surface of baffle 14. To prevent weather elements from entering into the motor compartments through louvers 25, each louver is provided with an outwardly and downwardly extending flange as shown more particularly in FIG. 1.

55 Another form of my invention is shown in FIG. 5 which is somewhat similar to the modification shown in FIGS. 1 to 4 and corresponding parts have accordingly 60 been designated by the same reference numerals. As shown, the ventilator is supported upon a curb 48 which surrounds an opening in the roof of a building and comprises a base 1 having a downwardly extending flange 65 surrounding the curb and an upwardly extending venturi-shaped opening or duct means 2, a motor plate 11 which

extends across the ventilator and has a downwardly extending peripheral wall portion 47 which terminates in an outwardly and downwardly extending baffle 14, and a dome 19 which forms a cover for the motor compartment and which terminates in an outwardly and downwardly extending baffle 49, and means associated with the duct means 2 are provided for completing the blower compartment and spacing the motor plate upwardly relative to the duct means and the dome upwardly relative to the motor plate. For this purpose, an annular wall designated generally by the numeral 5 is provided which has a downwardly extending peripheral flange 6 which is welded or otherwise secured to the duct means 2, a portion 7 which extends radially outwardly from the upper portion of flange 6, and a portion 8 which extends upwardly in a vertical or a substantially vertical direction relative to the base 1 and terminates in an inverted U-shaped flange 9. To space the motor plate from the wall 5 and the dome 18 from the motor plate, a plurality of bolts 50 are provided, each of which has its head arranged within the inverted U-shaped portion of flange 9 and extends upwardly through the inner portion of baffles 14 and 49 and is secured in place by a nut 51 threaded on to its upper end portion and for spacing the baffle 14 from the flange 9 and the baffle 49 from baffle 14, a sleeve 52 surrounds the portion of each bolt 50 extending between the flange 9 and the baffle 14 and a sleeve 53 surrounds the portion of each of the bolts 50 which extend between the upper portion of baffle 14 and the lower portion of baffle 49.

Motor 12 is supported upon and is secured to plate 11 by suitable means, such as bolts and nuts 13. In the form of the invention shown in FIG. 5, the shaft 54 of motor 12 extends through an opening in motor plate 11 and an opening in plate 25a, which forms the upper portion of the blower wheel, and terminates in a hub 35 to which it is secured by suitable means, such as a set screw, not shown, and consequently the shaft 54 of the motor serves to maintain the blower wheel in its desired rotatable position. To prevent the entrance of air from the blower compartment into the motor compartment, hub 35 is provided with a flange 36 which is secured to plate 25a by suitable means, such as bolts. In the modification shown in FIG. 5, the blower wheel which consists of plate 25a and a plurality of blades 26 is driven directly by the motor shaft. The blades 26 are preferably of the air foil type as shown more particularly in FIG. 2 and each blade may be provided with an upper flange which is secured to plate 25a by suitable means, such as rivets.

The upwardly extending portion 8 of the annular wall 5 is parallel to the blades 6 which permits the blower wheel to operate under a slight internal pressure, thereby improving its efficiency and in this respect the ventilator shown in FIG. 5 is similar to the ventilator shown in FIGS. 1 to 4. The wall 8 which extends upwardly perpendicular to or substantially perpendicular to the base portion 1 also prevents back pressure into the ventilator and terminates at such a distance from baffle 14 that the cross sectional area at the outlet from the blower compartment is the same or substantially the same as the cross sectional area of its air inlet means, thus providing a constant pressure in the blower compartment.

In the modification shown in FIG. 5, louvers 25 are formed in the dome which are similar to those shown in FIG. 1. When the blower is driven, air forced outwardly through its discharge opening between flange 9 and baffle 14 as indicated by the arrow B creates a negative pressure above baffle 14 and consequently air is also drawn outwardly from the motor compartment as indicated by the arrow A which is replenished by air entering the motor compartment through the louvers 25 as indicated by the arrows C. Because baffle 49 extends substantially parallel to baffle 14, it will be apparent that a greater negative pressure will be provided above baffle 14 in the modification shown in FIG. 5 than in the modification shown in

FIGS. 1 to 4, thereby causing an increased flow of air through the motor compartment to cool the motor. To energize the motor, a tubular member 55 is provided which extends upwardly through flange 9 and the baffle 14 and provides an opening through which insulated electrical conductors 45 may be passed to energize the motor.

Another modification of my invention is shown in FIGS. 6 and 7 which is similar to that shown in FIG. 5 with the exception that the motor is indirectly driven in the manner shown in FIGS. 1 to 4. The parts in FIGS. 6 and 7 which are similar to those shown in FIG. 5 have accordingly been designated by the same reference numerals as the corresponding parts in FIG. 5 and the parts in FIGS. 6 and 7 which are similar to those shown in FIGS. 1 to 4 have been designated by the same numerals as the corresponding parts in FIGS. 1 to 4.

The operation of the ventilator shown in FIGS. 6 and 7 is the same as that shown in FIG. 5 with the exception that the blower is driven by motor 12 through a belt drive 56. In this modification, the rubber collars between the plate 11 and the flanges 42 and 43 are shown more clearly than in FIGS. 1 to 4 and have been designated by the numeral 57. It will be noted that in the modification shown in FIGS. 5 and 6, the wall 8 extends upwardly in a vertical direction from base 1 and cuts off air which is forced outwardly by the lower portion of the blower, thus permitting the blower wheel to operate under a slight internal pressure which improves its efficiency and which provided with the air foil blades a ventilator that is quiet in operation. The vertical portion 8 of the annular wall also prevents back pressure into the ventilator and is of such height that the cross sectional area at the discharge outlet of the blower wheel is equal to the cross sectional area at its inlet opening, thereby providing a constant pressure in the blower compartment. The discharge of air through the annular opening between the flange 9 and the baffle 14 also creates a negative pressure above baffle 14 which is particularly pronounced in view of the fact that baffle 49 is substantially parallel to baffle 14, thereby causing a continuous flow of air from the atmosphere through the motor compartment to cool the motor.

Another modification of my invention is shown in FIGS. 8 and 9 which is somewhat similar to that shown in FIGS. 1 to 4 but instead of louvers, an annular inlet opening 58 is provided between the wall 17 and the dome 19. The blower is also driven directly by the shaft of the motor as shown in FIG. 5 and not indirectly as shown in FIGS. 1 to 4. Parts corresponding to the modification shown in FIGS. 1 to 4 have accordingly been designated by the same reference numerals as those shown in that modification and parts corresponding to the structure shown in FIG. 5 have been designated by the same numerals as those shown in that modification.

As shown in FIG. 8, the ventilator includes a base 1, a motor plate 11 having a downwardly extending peripheral wall 47 which terminates in an outwardly and downwardly extending baffle 14, a vertically extending wall 17, and a dome 19. As shown in FIG. 8, the wall 5 has a downwardly extending annular flange which is secured to the duct means by suitable means, such as rivets, a portion 7 which extends radially outwardly and then upwardly as designated by the numeral 8 in substantially parallel relation to the lower portion of the blades to provide a slight internal pressure in the blower compartment and which terminates in a U-shaped flange 9, and means are provided to maintain the motor plate at such a distance from the flange 9 that an annular discharge opening is provided that has substantially the same cross sectional areas as the inlet opening into the blower compartment. For this purpose, a plurality of lower posts 10 are provided which are internally threaded at their opposite ends in the manner shown in FIGS. 3 and 4, one end of each of which rests upon the base 1 and is secured thereto by a screw extending upwardly through

base and by screws 15, each of which is threaded into the upper portion of the lower post through an opening in the flange 9, and by upper posts 16 which are seated on to the upper portion of screws 15 and the upper portion of each of which engages the radially extending portion 18 of baffle 14 and means are provided for securing the radially extending portion of baffle 14 to posts 16 and maintaining wall 17 in spaced relation thereto to provide the annular outlet opening 20. For this purpose, a plurality of angularly-shaped brackets 21 are provided as shown more particularly in FIG. 4, one of each of which extends over the radially extending portion 18 of baffle 14 to which it is secured by a screw 24 which passes through apertures in the bracket and the radially extending portion 18 into the upper portion of each post 16. For spacing wall 17 upwardly relative to the radially extending portion of baffle 14, the other arm of each bracket is provided with a threaded bushing 22 as shown more particularly in FIG. 4 which is spaced upwardly from the radially extending portion 18 of the baffle and the wall 17 is held in spaced relation to the baffle 14 by the wing headed screws 23, each of which is threaded into a bushing 22 in the upwardly extending portion of the bracket.

Motor 12 is supported on plate 11 to which it is secured by bolts and nuts 13 and is provided with a shaft 34 which extends downwardly through openings in motor plate 11 and the plate 25a of the blower and extends into a hub 35 to which it may be secured by any suitable means, such as a set screw, not shown. Hub 35 is provided with an annular flange 36 which may be secured to plate 25a and which closes the opening through which the motor shaft 34 extends to prevent air from passing from the blower compartment to the motor compartment. As in previous modifications, the blower consists of a plurality of blades which are preferably of the air foil type, each of which is provided with an upper flange 26 which is riveted or otherwise secured to the plate.

As shown, motor shaft 34 holds the blower in the desired rotatable position and during the rotation of the blower, air discharged from the ventilator outwardly between the flange 9 and baffle 14 causes a negative pressure above the baffle 14 to cause air to flow outwardly from the motor compartment through the annular opening 20 which is replenished by air flowing into the motor compartment through the annular opening 58. The annular opening 58 may be provided in any desired manner. As shown, the wall 17 has an inwardly extending annular portion 59 as shown more particularly in FIG. 9 which terminates in an upwardly extending annular flange 60 which is spaced inwardly from the lower portion of dome 19 and has spaced apertures therein and a plurality of bolts 61 are provided, each of which extends through aligned openings in the lower portion of dome 19 and the flange 60 and is held in place by a nut 62. For maintaining the lower portion of dome 19 and the flange 61 in spaced relation, an annular spacer surrounding each bolt is interposed between the lower portion of dome 19 and the flange 60. It will be noted that the lower annular portion of dome 19 extends below flange 60 to thereby prevent the entrance of weather elements, such as rain, snow, or sleet, into the motor compartment through the annular opening 58. The wall 47 also limits the entrance of weather elements into the lower portion of the motor compartment and the baffle 14 prevents the entrance of weather elements into the blower compartment.

What is claimed is:

1. A ventilator including a base for application to a curb on the roof of a building and having an upwardly extending annular duct means, a radially extending circular first wall having a central aperture therein which is spaced upwardly from said duct means and terminates in an outwardly and downwardly inclined annular baffle, means for supporting said circular wall in spaced relation to said duct means, a rotatable blower arranged below said circular wall, means for providing a compartment for said blower including a second annular wall which extends substantially vertically upwardly relative to the base portion and which terminates at a sufficient distance below the upper portion of the blower and said first wall to define an annular opening for the egress of air from the blower compartment which has substantially the same cross sectional area as the cross sectional area of the inlet duct means, means for supporting said second wall, a motor supported on the radially extending first wall, and a shaft extending through

to said duct means, a rotatable blower arranged below said circular wall, means for providing a compartment for said blower including a second annular wall which surrounds said blower and terminates below the upper portion of said blower and said baffle but extends a sufficient distance vertically upwardly relative to the base above the lower portion of said blower to provide an annular outlet opening for the egress of air from said blower compartment which has substantially the same cross sectional area as the cross sectional area of the inlet duct means, means for supporting said second annular wall, a motor supported on the radially extending circular wall, a shaft extending through the central opening in the circular wall which is connected to the blower and which is rotatable by said motor, a housing for said motor including a wall portion extending above said motor and an annular side wall surrounding the motor, means for providing air inlet means leading into the upper portion of the motor housing, and means for spacing said motor housing upwardly from said baffle to provide an annular air outlet opening from the motor housing so that the egress of air from the blower compartment will create a negative pressure above said baffle to cause air to circulate through said motor housing during the rotation of said blower.

2. A ventilator as defined in claim 1 in which said wall portion extending over the motor and said annular side wall portion surrounding the motor are shaped to provide a dome and said side wall portion has louvers therein for providing the air inlet means into said motor housing.

3. A ventilator as defined in claim 1 in which the wall portion extending above the motor and the annular side wall portion are shaped to provide a dome and the air inlet means is in the form of louvers arranged in the side wall of the dome and in which said side wall portion of the dome terminates in an outwardly and downwardly extending baffle which is spaced upwardly at a sufficient distance from the baffle extending from said first circular wall to provide an annular opening above the first mentioned baffle so that air will be drawn outwardly from the motor housing during discharge of air from the motor compartment.

4. A ventilator as defined in claim 1 in which the housing for the motor includes a dome-shaped wall having louvers therein to provide the air inlet means and a third annular wall connected to but spaced upwardly relative to said baffle provides the annular outlet opening from said housing.

5. A ventilator as defined in claim 1 in which the housing for the motor includes a dome-shaped wall and a third annular wall and in which the third annular wall has its lower portion secured to but spaced upwardly from said baffle to provide the annular egress opening for air from said housing and in which the air inlet means into the motor housing is provided by an annular opening between said third wall and the dome-shaped wall.

6. A ventilator including a base portion for application to a curb on the roof of a building, said base portion having an upwardly extending annular duct means, a radially extending first circular wall having a central aperture therein which is spaced upwardly from said duct means and which terminates in an outwardly and downwardly inclined annular baffle, means for supporting said circular wall in spaced relation to said duct means, a rotatable blower arranged below said circular wall, means for providing a compartment for said blower including a second annular wall which extends substantially vertically upwardly relative to the base portion and which terminates at a sufficient distance below the upper portion of the blower and said first wall to define an annular opening for the egress of air from the blower compartment which has substantially the same cross sectional area as the cross sectional area of the inlet duct means, means for supporting said second wall, a motor supported on the radially extending first wall, and a shaft extending through

the central aperture of the first circular wall which is connected to the blower and is rotatable by said motor to draw air through said conduit means and force it outwardly through the annular opening between said baffle and the second wall.

7. A ventilator as defined in claim 6 including a housing for said motor having a dome-shaped wall and a downwardly and outwardly extending second annular baffle which is spaced upwardly from said baffle on the first circular wall to provide an annular opening for the egress of air from the motor housing when said blower is rotated to draw air from the conduit means and discharge it between the downwardly extending baffle on the first wall and the upper end of the second annular wall, and means for supporting the dome-shaped wall of said housing in spaced relation to the downwardly and outwardly extending second annular baffle to provide an annular opening for air leading into said housing.

8. A ventilator as defined in claim 6 in which the circular first wall has a downwardly extending annular portion adjacent its periphery to limit the entrance of weather elements between said upwardly extending wall and said baffle.

9. A ventilator as defined in claim 6 in which a housing is provided for the motor which includes a vertically extending wall and a dome-shaped wall, means for spacing the vertically extending wall upwardly from said baffle to provide an annular opening for the egress of air from said housing and said vertically extending wall being provided with an inwardly extending portion at its upper end which terminates in an upwardly and inwardly inclined flange which is arranged inwardly of the lower portion of said dome-shaped wall, and means for connecting the dome-shaped wall to said flange and for spac-

ing it therefrom to provide an annular opening for the entrance of air into the motor housing.

10. A ventilator including a base portion for application to a curb on the roof of a building, said base portion having an upwardly extending annular duct means, a radially extending first circular wall having a central aperture therein which is spaced upwardly from said duct means and terminates in an outwardly and downwardly inclined annular baffle, means for supporting said circular wall in spaced relation to said duct means, a rotatable blower arranged below said circular wall and having blades which extend radially outwardly a substantial distance beyond said duct means, means for providing a compartment for said blower including a second annular wall having an annular flange secured to the outer periphery of said duct means, an annular portion which extends radially outwardly beyond the blades of said blower, and a portion which extends vertically upwardly and terminates in an inverted U-shaped flange, and said upwardly extending portion of said second wall terminating at a sufficient distance from the inner portion of said baffle to provide an outlet opening from the blower compartment which has substantially the same cross sectional area as the cross sectional area of said inlet duct means.
